UNITED STATES PATENT OFFICE.

JOHN ST. JOHN, OF BRIDGEPORT, CONNECTICUT, ASSIGNOR TO THE SMITH & EGGE MANUFACTURING COMPANY, OF SAME PLACE.

DESIGN FOR A BROOM-HOLDER.

SPECIFICATION forming part of Design No. 19,101, dated May 14, 1889.

Application filed February 6, 1889. Serial No. 298,904. Term of patent 7 years.

To all whom it may concern:

Be it known that I, JOHN ST. JOHN, a citizen of the United States, residing at Bridgeport, in the county of Fairfield and State of Connecticut, have invented and produced a new and original Design for a Broom-Holder; and I do hereby declare the following to be a full, clear, and exact description of the invention, such as will enable others skilled in the art to which it appertains to make and use the same.

The drawing shows a perspective of a broom-holder designed in accordance with my invention.

The leading features of my design consist in an alternate series of parallel openings and bars extending transversely of said holder.

A is the holder, B the parallel openings, and C the parallel bars. The openings B are bounded by curved lines, are of the same size at the top and bottom, and are narrowest at the central portions, while the bars C are also bounded by curved lines, are of the same size at the ends, and are bellied at the central portions.

I claim—

The design for broom-holders, substantially as set forth and shown in the accompanying specification and drawing.

In testimony whereof I affix my signature in presence of two witnesses.

JOHN ST. JOHN.

Witnesses:

RICHARD H. BRODERICK,
J. H. GREEN.
